UNITED STATES PATENT OFFICE.

GEORGE H. HOLLAND, OF ST. LOUIS, MISSOURI, ASSIGNOR TO THE BRIDGE & BEACH MANUFACTURING COMPANY, OF SAME PLACE.

DESIGN FOR A COOKING-STOVE.

SPECIFICATION forming part of Design No. 21,807, dated August 30, 1892.

Application filed July 30, 1892. Serial No. 441,772. Term of patent 14 years.

To all whom it may concern:

Be it known that I, GEORGE H. HOLLAND, a citizen of the United States, residing in the city of St. Louis, State of Missouri, have invented and produced a new and original Design for Cooking-Stoves, of which the following is a specification, reference being had to the accompanying drawing, forming a part thereof.

10. The drawing represents a perspective view of the stove, taken from a point of view somewhat above the level of the top of the stove and a short distance in front, taking the front to be that end of the stove from which the 15 ash-pit projects.

The leading features of my design in the stove as a whole are the following: The top casting extends beyond the sides and ends of the body of the stove, terminating in a downwardly-convex-curved edge. The rear portion in the middle from side to side is formed with the raised flange for the pipe. To the back end is the extension warming-shelf, and at one of the rear end corners of the top 25 casting is the tea-pot shelf. The front fire-box door is formed straight from end to end, the upper and end edges being convex curved, making the body of the door stand out from the front of the stove, giving it the appearance of a thick casting, the upper portion of the door being stippled or roughened and the lower portion having formed therein the openings for the draft. The hearth-plate extends forward from the bottom of the front 30 fire-box door, the edges thereof being convex curved downward similar to the top casting, the side edges extending, after they are inclined upward, from the line of the front of the fire-box, and then on a level back along the 35 sides of the stove to a distance corresponding to the rear edge of the side fire-box door. Beneath the hearth-plate is the ash-pit, which is formed with inclined sides and front and is comparatively shallow, extending to approximately one-third of the distance to the level of the bottom of the stove. The side fire-box door is formed with an inclined rear edge and is ornamented with a branch of a grape-vine with attached bunch of grapes 45 and leaves. The forward edge of the side plates of the stove extend vertically down-

ward from the lower side of the hearth-plate on a line corresponding approximately to the front side of the fire-box and then gently curved toward the back of the stove until the 55 curve becomes tangential to the vertical, where it meets the bottom plate of the stove, which projects all around beyond side and end plates of the stove in a convex-curved edge corresponding to the edges of the top 60 casting and hearth-plate. The oven-door is formed with straight edges at the top and bottom and back, the lower edge being longer than the upper, the upper forward corner being cut away to allow for the fire-box. The 65 front edge of the door is vertical to where it is cut away immediately under the rear side of the side fire-box door, leaving a space between it and the front edge of the side plate of the stove exposed, which is ornamented 70 with a branch of a grape-vine extending diagonally across the same from the lower front corner to the upper rear corner. To the branch is attached leaves and bunches of grapes, and there is perched thereon a bird 75 in the act of picking at one of the bunches of grapes. In approximately the center of the door is a medallion-plate, in the center of which is a bunch of grapes in relief. The door as a whole is formed with rounded or 80 curved edges, except at the bottom edge, making the door convex or pillar shaped on the exterior. Extending along the side of the stove, of about the length of the oven-door, is secured the extension oven-bottom 85 shelf, on which is a scroll of grape-leaves in relief on a stippled or roughened background.

The stove as a whole is mounted on the base, which joins the bottom plate and curves outwardly in approximately a quadrant of a 90 circle. The lower edge is formed with a double raised head, which at the corners curves up to the upper margin of the base and there turns on itself, terminating in a number of radial sprays. The base as a 95 whole is ornamented with two branches of grape-vine, the stock ends of which are crossed at the middle of the length of one side, surmounted with a bunch of grapes extending toward either end and provided with leaves, 100 all in raised work on a stippled or roughened groundwork. The base rests on the four feet,

which are arranged on the diagonals from corner to corner, curved outwardly at the bottom, and tapering in a gentle curve from the comparatively wide tops to the lower extremities. The general shape of the exterior surface as looked at diagonally across one of the corners is a compound curve, the upper member of which corresponds to the curve given to the cross-section of the base.

I claim—

The design for a cooking-stove, substantially as shown and described.

In testimony whereof I hereto affix my signature, in the presence of two witnesses, this 26th day of May, 1892.

GEO. H. HOLLAND. [i. s.]
